(57) **CLAIM**

The ornamental design for an adaptor for connecting a flat circuit device to an electrical connector, as shown and described.

DESCRIPTION

FIG. 1 is a front, top and left side perspective view of an adaptor for connecting a flat circuit device to an electrical coaxial, which shows my new design;

FIG. 2 is a front, bottom and left side perspective view thereof;

FIG. 3 is a top plan view thereof;

FIG. 4 is a bottom plan view thereof;

FIG. 5 is a front view thereof;

FIG. 6 is a rear view thereof;

FIG. 7 is a right side view thereof, the left side view is a mirror image thereof; and,

FIG. 8 is a reference front, top and left side perspective view of the adaptor put in practical use.

The broken lines in the FIGS. 1-7 illustrate portions of the adaptor for connecting a flat circuit device to an electrical connector which form no part of the claimed design. The broken line portions shown in FIG. 8 illustrates environmental subject matter only and form no part of the claimed design.

1 Claim, 8 Drawing Sheets
